UNITED STATES PATENT OFFICE.

CONRAD H. MATTHIESSEN, OF ODELL, ILLINOIS.

ADJUSTABLE BEDSTEAD.

SPECIFICATION forming part of Letters Patent No. 327,699, dated October 6, 1885.

Application filed September 24, 1884. Serial No. 143,886. (No model.)

To all whom it may concern:

Be it known that I, CONRAD H. MATTHIESSEN, of Odell, in the county of Livingston and State of Illinois, have invented a new and Improved Adjustable Bedstead, of which the following is a full, clear, and exact description.

The object of my invention is to provide a new and improved bedstead which can readily be adjusted higher or lower at the foot end, and whereby any desired inclination can be given to the bedstead from the head to the foot end.

The invention consists in the combination, with a bedstead, of a supporting-frame provided at the foot with toothed plates for holding a rod that supports the foot end of the bedstead.

The invention further consists in the combination, with the bedstead side rails, of longitudinally-apertured end posts, and of heavy screw-bolts passed through the apertured end posts, and through eyes and apertured plates on the end pieces of the bedstead, to connect the side rails and end pieces.

The invention also consists in parts and details and combinations of the same.

Reference is to be had to the accompanying drawings, forming part of this specification, in which similar letters of reference indicate corresponding parts in all the figures.

Figure 1 is a longitudinal elevation of my improved adjustable bedstead, parts being broken out and others in section. Fig. 2 is a plan view of the same. Fig. 3 is a detail sectional view of one of the end pieces of the bedstead.

The bedstead consists of two combined parts—the bedstead proper and the support for the same.

The bedstead proper is constructed with two side rails, A, provided with end posts, B, having apertures C extending from top to bottom.

A slot, E, is formed in the inner side of each end post, B, near the bottom, which slot serves to receive a plate, F, projecting from the corresponding end edge of the corresponding end piece, G, at the bottom, the projecting

part of the plate F being provided with a screw-threaded aperture.

A staple or eye, H, projects from the end edge of each end piece, G, near the top, the said staples or eyes resting on the upper ends of the posts B when the plates F are in the slots.

Heavy screw-bolts I, provided at their upper ends with heads I', are passed through the eyes H, the apertures C in the posts B, and are screwed into the apertured ends of the plates F within the posts B.

The plates F are secured by means of screws to the bottom edges of the end pieces, G.

On the inner surface of the bottom or foot end piece, G, a cushion or foot-rest, T, is held by an elastic band, J, or by other devices.

The bedstead-support consists of two end frames, K and L, united by side rails, M, the frame K having a cross-bar, N, on which the upper or head ends of the bedstead side rails, A, can rest, blocks N' being secured to the bottom edges of the rails A to hold the said rails in place on the cross-bar N.

On the inner sides of the posts of the foot-frame L plates P are secured, which are notched to form upwardly-projecting teeth 75 for supporting a cross-rod, R, having end heads, S, for preventing the rod from sliding off.

The head end of the bedstead rests on the cross-bar N of the frame K between the end 8c posts of the frame, and the foot end of the bedstead rests on the rod R between the posts of the frame L.

The foot end of the bedstead can be held higher or lower by placing the rod R on teeth 85 of the plates P a greater or less distance from the upper ends of the said plates.

Having thus described my invention, what I claim as new, and desire to secure by Letters Patent, is—

1. The combination, with the frames K and L, of the rails M uniting them, the plates P, secured to the legs of the frame L, and having upwardly-projecting teeth, and the rod R, having heads S on the ends, substantially 95 as herein shown and described.

2. The combination, with a bedstead, of a supporting-frame having a rigid cross-piece for supporting the head end of the bedstead, and a vertically-adjustable cross-rod for supporting the foot end of the bedstead, substantially as herein shown and described.
3. The combination, with the bedstead side rails, A, having longitudinally-apertured end

posts, B, of the end pieces, G, the eyes H, the apertured projecting plates F, and the screw-bolts I, substantially as herein shown and described.

CONRAD H. MATTHIESSEN.
